DESIGN FOR A RUFFLER ATTACHMENT
HOUSING FOR SEWING MACHINESVictor J. Sigoda, Great Neck, N. Y., assignor to
Man-Sew Corporation, New York, N. Y., a cor-
poration of New York

Application April 10, 1947, Serial No. 138,291

Term of patent 14 years

(Cl. D70—2)

To all whom it may concern:

Be it known that I, Victor J. Sigoda, a citizen of the United States residing at Great Neck, in the county of Nassau and State of New York, have invented a new, original, and ornamental Design for Ruffler Attachment Housing for Sewing Machines, of which the following is a specification, reference being had to the accompanying drawing, forming a part thereof.

Figure 1 is a perspective view of my new ruffler attachment housing for sewing machines;

Figure 2 is a transverse sectional view taken substantially on the line 2—2 of Figure 1;

Figure 3 is a similar sectional view taken substantially on the line 3—3 of Figure 1; and

Figure 4 is an end elevation of the ruffler attachment housing for sewing machines.

I claim:

The ornamental design for a ruffler attach-
ment housing for sewing machines, substantially
as shown.

VICTOR J. SIGODA.
